UNITED STATES PATENT OFFICE

140,915

DESIGN FOR A DOLL

Sue McCrory, Houston, Tex.

Application December 12, 1944, Serial No. 116,865

Term of patent 14 years

(Cl. D34—4)

To all whom it may concern:

Be it known that I, Sue McCrory, a citizen of the United States residing at Houston in the county of Harris, in the State of Texas, have invented a new, original, and ornamental Design for a Doll, of which the following is a specification, reference being had to the accompanying drawing, forming a part thereof.

I claim:

The ornamental design for a doll, as shown.
SUE McCRORY.
